DESIGN FOR A BABY'S CHAIR HARNESS

Ida M. Creed, San Francisco, Calif.

Substituted for abandoned application Serial No.
85,104, May 20, 1939. This application August
24, 1940, Serial No. 94,605

Term of patent 3½ years

To all whom it may concern:

Be it known that I, Ida M. Creed, a citizen of the United States residing at the city and county of San Francisco and State of California, have invented a new, original, and ornamental Design for Baby's Chair Harness, of which the following is a specification, reference being had to the accompanying drawing forming part thereof.

This application is substituted for Serial No. 85,104, filed May 20, 1939 now abandoned.

In the drawing:

Fig. 1 is a front view of a baby's chair harness showing my new design;

Fig. 2 is a rear view of the baby's chair harness shown in Fig. 1; and

Fig. 3 is a side view of the baby's chair harness shown in Fig. 1.

I claim:

The ornamental design for a baby's chair harness, substantially as shown.

IDA M. CREED.
